UNITED STATES PATENT OFFICE.

FREDERICK SARGENT AND HERMAN C. HEATON, OF CHICAGO, ILLINOIS, ASSIGNEES TO THE BABCOCK & WILCOX COMPANY, OF BAYONNE, NEW JERSEY, A CORPORATION OF NEW JERSEY.

APPARATUS FOR WASHING AND UTILIZING WASTE BOILER-GASES.

1,235,928.

Specification of Letters Patent.

Patented Aug. 7, 1917.

Application filed April 24, 1916. Serial No. 93,109.

To all whom it may concern:

Be it known that we, FREDERICK SARGENT and HERMAN C. HEATON, citizens of the United States, residing at Chicago, in the 5 county of Cook and State of Illinois, have invented certain new and useful Improvements in Apparatus for Washing and Utilizing Waste Boiler-Gases, of which the following is a specification.

10 Our invention relates to apparatus for washing and utilizing waste gases, and has been designed more particularly for use in connection with steam boilers. It will be understood by reference to the accompanying 15 drawings in which Figure 1 is a vertical section through a steam boiler plant containing our special washing apparatus, and Figs. 2 and 3 are similar views showing modified arrangements. In all of the drawings the 20 views are more or less diagrammatic.

Referring to Fig. 1, the numeral 1 designates a bank of inclined generating tubes expanded into front and rear headers, said headers being connected by pipes to a steam 25 and water drum 2. The boiler is fired by a stoker 3, the bank of tubes being divided by baffles to direct the gases toward the uptake ends of the tubes. Above the bank of generating tubes is a superheater 4, and above 30 the latter is an economizer 5. These parts may be of any usual and well-known design and connected in a known manner, as indicated in the drawings. The flow of the gases over the boiler tubes, superheater and economizer is indicated by arrows.

35 6 indicates the washing chamber which is preferably set above the economizer. This washer may be of any suitable or convenient form having an opening near the lower part 40 thereof for the admission of smoke and gases from the flue 7, and an outlet at the top thereof into an induced draft fan 8 or other suction device, from which they are forced to the stack or uptake. The wash water is 45 sprayed into the chamber through a suitable spraying device, such as a perforated coiled pipe 9, in the upper part of the chamber, connected to a water supply pipe 10.

In the particular arrangement shown, 50 water is admitted to the chamber 6 through a pipe 11, the level of the water being controlled by a float valve 12. Leading from the lower part of the chamber 6 is a pipe 13

connected to a feed water heater 14, the water being drawn through said pipe and 55 heater by a centrifugal pump 15, and then by the latter forced through the pipe 10 to the sprayer 9. The heater 14 may be cleaned of mud or other deposits through a blow-off valve 14'. The wash water is sprayed downward through the gases so as to obtain the benefit of the counter-flow principle, that is, the colder water comes in contact with the 60 colder gases, and the hotter water with the hotter gases. The water, after spraying through the gases, collects in the lower part of chamber 6, the volume of the water being maintained substantially constant by means of the float valve 12. The dust or soot removed from the gases in chamber 6 is flushed 70 out through a large valve 16.

The feed water, obtained from the hot well, or any other source, is forced by the pump 17 through the pipe 18 to the coil of pipe 19 in the heater 14, said coil being 75 surrounded by the hot water delivered to the heater through pipe 13. The feed water is made to flow through coil 19 in a reverse direction to the flow of the water through the heater, and in this way the counter-flow 80 principle is again made use of. The upper end of the coil of pipe 19 is connected by a pipe 20 leading to the economizer 5, from which it passes by a pipe 21 to the steam and water drum 2. 22 is the main steam 85 valve through which the steam is discharged from the boiler, or to the superheater 4.

23 indicates a fan for delivering air to the stoker boxes 24.

In Fig. 2 we have shown a modified arrangement in which the water from the washing chamber 6, after flowing to the feed water heater 14, is delivered through a pipe 25, leading from the lower part of the heater, to a sprayer 26 in the upper part of 90 a chamber 27. Above the level of the water in the chamber 27 is an air inlet pipe 28, and in the upper part thereof an air outlet leading to the fan 23, from which the air is delivered to the stoker boxes 24. The 95 purpose of the spraying chamber 27 is to saturate the air with moisture before it is delivered to the stoker boxes. The saturation of the air entering the furnace is for the purpose of increasing the efficiency 100 of an economizer in which moisture is con- 105

densed from the furnace gases, and is de-
scribed more fully in an application for
patent Serial No. 876,016, filed December 8,
1914. The water from the air-moistening
5 chamber 27 is forced by pump 15 through
pipe 10 to the sprayer 9 in the upper part
of the gas washing chamber 6. In the ar-
rangement shown in Fig. 2 the water to
make up for evaporation or leakage is sup-
10 plied to the air-moistening chamber 27
through the pipe 29, the level of the water
being controlled by a float valve.

In Fig. 3 we have shown a further modi-
fication which consists essentially in omit-
15 ting the feed water heater of Fig. 2, that
is, the water from the gas-washing chamber
6, instead of being delivered to a feed water
heater, is delivered directly through the pipe
13 to the sprayer 26 in the upper part of the
20 air-moistening chamber 27. In this arrange-
ment the feed water is drawn from the hot
well and delivered by the pump 17 through
the pipe 30 direct to the economizer 5.

A further modification is shown in the
25 form of the sprayer used in the gas-washing
chamber 6. Instead of a perforated pipe, we
have shown, in Fig. 3, a series of inclined
and perforated wooden shelves or gratings
31 similar to those used in cooling-towers,
30 the water being broken up as it flows over
the shelves and through the openings therein.

Among the advantages secured by our in-
vention are that the gases leaving the boiler
are washed free from soot and dust, and the
35 annoyance from the deposition of soot and
dust over surrounding property is avoided.
Also some of the heat which would other-
wise be wasted in the gases is returned to
the feed water, or is utilized in heating and
40 saturating the air for combustion, and in
both cases additional economy is thereby se-
cured.

Instead of using water in the chamber 6
we may use some other liquid, as for exam-
45 ple, a heavy non-inflammable oil, with a
higher vaporizing point than water.

What we claim and desire to secure by
Letters Patent of the United States is:—

1. In a steam boiler plant, a conduit
through which the waste gases pass, means 50
for spraying the gases therein, a feed water
heater, and a conduit arranged to conduct
the heated spray liquid to the feed water
heater, the heater being arranged to keep
the feed water separated from the spray 55
liquid while conducting heat from the latter
to the feed water.

2. In a steam boiler plant, a conduit
through which the waste gases pass, means 60
for spraying the gases therein, a feed water
heater, a conduit arranged to conduct the
heated spray liquid to the feed water heater,
and means for conducting the feed water
through said heater in a direction opposite 65
to the flow of the heated spray liquid therein.

3. In a steam boiler plant, a conduit
through which the waste gases pass, means
for spraying the gases therein, a feed water
heater, and a conduit arranged to conduct
the heated spray liquid to the feed water 70
heater, the heater being arranged to keep
the feed water separated from the spray
liquid while conducting heat from the latter
to the feed water, and a pump for returning
the spray liquid from said heater to the gas 75
washing chamber.

4. A steam boiler plant comprising a
chamber to which the waste gases are de-
livered, means for spraying water into said
chamber, a feed water heater, a chamber for
moistening the air for combustion, and
means for passing the hot wash water 80
through said heater and for spraying it in
said air-moistening chamber.

In testimony whereof we have hereunto 85
signed our names in the presence of two
subscribing witnesses.

FREDERICK SARGENT.
HERMAN C. HEATON.
